UNITED STATES PATENT OFFICE.

CHARLES BERGNER, OF ROCHESTER, NEW YORK, ASSIGNOR TO C. T. HAM MANUFACTURING COMPANY, OF ROCHESTER, NEW YORK.

LANTERN.

No. 920,525.

Specification of Letters Patent.

Patented May 4, 1909.

Application filed November 21, 1907. Serial No. 403,118.

To all whom it may concern:

Be it known that I, CHARLES BERGNER, a citizen of the United States, residing at Rochester, in the county of Monroe and State of New York, have invented a new and useful Improvement in Lanterns, of which the following is a specification.

This invention relates to that class of lanterns in which the oil pot is removably arranged within the body hoop or globe ring, as, for instance, in railroad lanterns in which the body hoop or globe ring, which is secured to or supported by the upright members of the guard, supports the globe which is inserted into the basket-shaped guard from above and rests upon the upper edge of the body hoop or globe ring.

The objects of this invention are to produce a lantern of this character in which the oil pot is securely held in position by simple, compact and convenient devices, which permits the ready removal of dirt from the body hoop or globe ring, and in which the wick raiser shaft extends outside of the body hoop and can be manipulated without requiring the removal of the oil pot from the body hoop.

In the accompanying drawings: Figure 1 is a sectional elevation of a lantern provided with my improvements. Fig. 2 is a side elevation of the lower part of the lantern. Fig. 3 is a horizontal section in line 3—3, Fig. 1. Fig. 4 is a vertical section of the lower part of the lantern at right angles to Fig. 2.

Like reference characters refer to like parts in the several figures.

20 represents the body hoop or globe ring, 21 the upright guard members secured thereto, 22, 23, 24, 25 the horizontal guard rings, 40 26 the top hinged to the uppermost guard ring 22, and 27 the globe which rests on the upper edge of the body hoop or globe ring by its bottom shoulder 28 and is held down upon the body hoop by the top in the usual way. The body hoop or globe ring is provided at its lower end with an inwardly projecting annular bottom or flange 29 which surrounds a central opening 30.

31 represents the oil pot which rests loosely on this bottom and is centered on the same by any suitable means, for instance, at the top by projections 32 on the inner side of the body hoop, which projections may be formed, as shown, by the bent portions of the upright guard members, and at the bot-

tom by the annular depression or shoulder 33 in the annular bottom flange.

34 represents the burner which is secured to the oil pot by any suitable means, and 35 represents arms which extend sidewise from the burner and receive the lower edge 36 of the globe. When the latter rests upon the body hoop it bears also upon the arms 35 of the burner and clamps the oil pot down upon the annular supporting flange 29 of the body hoop, thereby holding the oil pot firmly in position within the body hoop without the employment of special fastening devices for that purpose. The clamping arms are preferably made flexible or elastic to better adjust themselves to the bottom of the globe.

Upon releasing the top 26 and removing the globe the oil pot is released and can be lifted out of the body hoop. The latter is provided in its upper edge with a notch 37 for the wick raiser shaft 38 which has its manipulating disk 39 arranged outside of the body hoop, where it can be turned for adjusting the wick when the globe is in place without disturbing the oil pot, thereby avoiding the inconveniences which attend the removal of the oil pot for that purpose in most railroad lanterns. The removal of the oil pot from the body hoop uncovers the opening 30 in the annular bottom 29. Any dirt which may have lodged in the body hoop can be readily removed through this opening.

I claim as my invention:

1. In a lantern, the combination of a body hoop having a bottom permanently secured thereto, an oil pot resting loosely on said bottom and provided near its top with a laterally projecting holding device, a globe resting above its lower end directly upon the body hoop and bearing with its lower end upon said holding device, and a movable top for holding the globe removably upon the body hoop and holding device, substantially as set forth.

2. In a lantern, the combination of a body hoop having a bottom permanently secured thereto and provided with an opening which is surrounded by said bottom, an oil pot resting loosely on said bottom over said opening and provided near its top with a laterally projecting holding device, a globe resting above its lower end directly upon the body hoop and bearing with its lower end upon said holding device, and a movable

top for holding the globe removably upon the body hoop and holding device, substantially as set forth.

3. In a lantern, the combination of a body hoop having a bottom secured thereto and provided in its upper edge with a notch, an oil pot resting loosely on said bottom and provided with a wick-raiser shaft which extends outwardly through said notch, a laterally projecting holding device carried by said oil pot near the top thereof, a globe resting above its lower end directly upon the body hoop and bearing with its lower end upon said holding device, and a movable top 10 for holding the globe removably upon the body hoop and holding device, substantially as set forth.

4. In a lantern, the combination with an oil pot, of a body hoop having a bottom secured thereto and provided with a central depression for supporting and centering the oil pot, the oil pot resting loosely on said bottom within said depression, a laterally projecting holding device on said oil pot, a globe resting directly on said body hoop and bearing upon said holding device, and means 20 for holding the globe in place, substantially as set forth.

5. In a lantern, the combination with an oil pot, of a body hoop having a bottom 30 permanently attached thereto and adapted to receive the oil pot from above, the oil pot resting loosely on said bottom and being provided with a laterally projecting holding device, a globe resting directly upon said body hoop and bearing upon said holding device for holding the oil pot on said bottom, and a movable top bearing upon the globe, substantially as set forth.

6. In a lantern, the combination with an oil pot, of a body hoop having a bottom 40 permanently attached thereto and adapted to receive the oil pot from above, the oil pot resting loosely on said bottom and being provided with laterally projecting flexible holding arms, a globe resting directly upon said body hoop and bearing upon said holding arms for holding the oil pot on said bottom, and a movable top bearing upon the globe, substantially as set forth.

Witness my hand in the presence of two subscribing witnesses.

CHARLES BERGNER.
